UNITED STATES PATENT OFFICE.

NATHANIEL KINNEY, OF AMITY, DEMOCRACY, OHIO.

PEGGING-JACK.

SPECIFICATION forming part of Letters Patent No. 374,744, dated December 13, 1887.

Application filed October 4, 1887. Serial No. 251,419. (No model.)

To all whom it may concern:

Be it known that I, NATHANIEL KINNEY, of Amity, Democracy P.O., in the county of Knox and State of Ohio, have invented a new and 5 Improved Pegging-Jack, of which the following is a full, clear, and exact description.

This invention relates to an improvement in pegging-jacks for holding boots or shoes; and it consists in a pegging-jack constructed as 10 hereinafter described and claimed.

The object of the invention is to provide a pegging-jack which is adapted to be raised and lowered, so that work may be performed upon a boot or shoe held thereon at different 15 heights.

The pegging-jack constructed in accordance with this invention is made in sections so connected that the upper section carrying the shoe-clamp may be lowered and raised to adapt 20 it to different heights.

Reference is to be had to the accompanying drawings, forming a part of this specification, in which similar figures of reference indicate corresponding parts in all the views.

25 Figure 1 is a side view of the pegging-jack, the sections resting upon one another. Fig. 2 is an end view thereof. Fig. 3 is an end view showing the upper section of the pegging-jack lowered in a tilting position, and Fig. 4 30 is an end view showing the upper section in position for pounding leather.

In constructing my pegging-jack I form it in sections 1 2, connected together in any suitable manner, so that the upper section may be 35 lowered and raised adjacent to the lower section. As here shown, I have connected the sections by means of links or pivoted arms 3, mounted on pins 4, extending through the uprights 5 of the sections. The lower section, 2, 40 has its uprights 5 resting upon a base, 6, one of said uprights being secured thereto and the other being provided with a slot, 7, which fits over a rail or rib, 8, on the base 6, on which it is adapted to be moved. The upright just 45 mentioned, together with the upright of the upper section resting thereon, is adjustably connected with the opposite uprights by means of bars 9, projecting through openings 10 in the uprights 5, said bars being provided with 50 slots 11, with which latches 12, adapted to rest in a hook, 13, engage. By the construction just described the movable uprights are ad-

justable toward the fixed uprights to provide for shoes of different lengths resting on the upper edges of the upper section.

55

To clamp a boot or shoe in place, I provide a lever, 14, which may be mounted in the upper section in any suitable manner. I have shown it having one end pivoted in a slot, 15, to a pin, 16, in a rotating bar, 17, mounted in 60 bearings 18 on the upright 5. By means of this connection the lever 14 may have a vertical and lateral movement, for a purpose hereinafter described. The lever 14 is provided with a strip, 20, having an edge, 21, which is 65 adapted to engage notches 22 in a plate, 23, on the upright 5. The lever 14, with its plate 20, projects through an opening, 19, in the upright 5, and by means of a handle, 24, and the pivot-joint of the lever 14 the latter may 70 be swung vertically and laterally into and out of engagement with the notched plate 23, and thereby secure and release an endless strap, 25, on the lever 14, which serves to hold a shoe, 26, against pads 27, formed of leather or other 75 proper material suitably stuffed and mounted on the upright 5. The pads 27 serve to prevent the shoe from becoming soiled.

The upper section is provided with a pounding-block, 28, attached thereto at any convenient point. The sections may be made of suitable length, so that when resting upon one another the top of the upper section will be at a convenient height for a workman to work 80 upon a shoe in a standing position.

85

In order to render the jack convenient for a workman when sitting down to work upon a shoe, the upper section is moved off of the lower section and swung down until it rests on the base 6 adjacent to the lower section, as 90 shown in dotted lines in Fig. 2.

When it is desired to use the pounding-block 28 for pounding leather, the upper section may be turned over, so as to rest horizontally on the lower section, and the pounding-block will 95 then be in a convenient position for use.

By means of this invention the pegging-jack is easily adapted for pegging, sewing, or patching shoes in a raised or lowered position.

I do not desire to limit myself to the precise 100 construction and arrangement of parts shown, as the same may be varied without departing from the principle of my invention.

Having thus fully described my invention,

what I claim as new, and desire to secure by Letters Patent, is—

1. The pegging-jack herein described, formed of sections resting upon one another and connected by pivoted bars, whereby the upper section may be brought down and placed in an upright position adjacent to the lower section, substantially as described.

2. The pegging-jack herein described, consisting of sections resting upon one another and connected by pivoted links or bars, the lower section having one of its uprights fixed to a base and the other together with the upright of the upper section, adjustably connected to the opposite uprights, substantially as described.

3. In the pegging-jack herein described, the combination, with the lower section having a fixed and adjustable upright connected together and mounted on a base, of an upper movable section connected to the lower section by pivoted links and having a fixed and ad-

justable upright connected together, and a lever and endless strap, said lever being adapted to be adjustably locked, substantially as described.

4. The pegging-jack herein described, formed of sections having pivotal connections, whereby the upper section may be tilted to rest upon the lower section, the upper section being provided with a pounding-block, substantially as described.

5. A pegging-jack consisting of the sections 1 2, connected by pivoted links 3, said sections being formed of uprights 5, adjustably connected by the slotted bars 9 and latches 12, and the upper section being provided with a notched plate, 23, a flanged lever, 14, an endless strap, 25, and padded ends 27, substantially as described.

NATHANIEL KINNEY.
